DANIEL A. PAGE, OF DOVER, NEW HAMPSHIRE.

Design No. 3,984, dated April 19, 1870.

DESIGN FOR A TRADE-MARK.

The Schedule referred to in these Letters Patent and making part of the same.

To all persons to whom these presents may come:

Be it known that I, DANIEL A. PAGE, of Dover, of the county of Strafford and State of New Hampshire, have invented or produced a new ornamental Design for a Trade-Mark, which I do hereby declare to be represented in the accompanying drawing and to be thus described:

It consists of a boot, a, with its leg having on one flank an awl, b, and on the other a pair of shoemak-ers' pincers, c, the whole being inclosed within a circle, d.

The boot, awl, pincers, and circle, arranged as represented, constitute the design for a trade-mark.

I claim as my invention or production—

The above-described design.

Witnesses: DANIEL A. PAGE.
